FLATCAR

Filed April 29, 1935

UNITED STATES PATENT OFFICE

2,042,260

FLATCAR.

Augustus F. Klasing, Chicago, Ill.

Application April 29, 1935, Serial No. 18,948

2 Claims. (Cl. 105—461)

Flat cars as hitherto provided present the objection of being unprovided with any means extending above the deck of the car which may be grasped by the trainmen in the mounting of the 5 deck or in the setting of the brakes. The lack of such means renders difficult, if not dangerous, the mounting of the deck by the trainmen and the setting of the brakes with one hand while holding onto the car with the other, the usual grab 10 iron provided on flat cars adjacent the steps thereof being located at the elevation of the decks, and thus at too low an elevation to be satisfactory.

While the grab iron extending above the deck 15 to a suitable height adjacent the step would overcome the objections above noted, such has not hitherto been provided inasmuch as such a grab iron would present obstruction to the loading and unloading of the car and would thus be thoroughly 20 impracticable.

My object is to provide for the equipping of a flat car with a grab iron device which may be moved at will into and out of a position in which it projects above the deck of the car into operative position, thus permitting it to be removed from a position in which it would obstruct the free loading and unloading of the car.

Referring to the accompanying drawing:

Figure 1 is a view in side elevation of one end 30 of a flat car showing it as equipped with a grab iron in accordance with my invention.

Figure 2 is a plan view of the structure shown in Fig. 1.

Figure 3 is a section taken at the line 3—3 on 35 Fig. 1 and viewed in the direction of the arrow showing by full lines the grab iron in raised, operative, position and by dotted lines the position it occupies when lowered and freeing the car of obstruction to the loading and unloading thereof.

Figure 4 is an enlarged fragmentary plan sectional view taken at the line 4 on Fig. 1 and viewed in the direction of the arrow; and

Figure 5, a bottom plan view of the structure shown in Fig. 4 and representing the grab iron in 45 section.

The construction of a flat car shown comprises, in accordance with common practice, the deck represented at 6 and supported on the metal side 50 sills 7 and end sills 8, a step 9 secured to one of the side sills adjacent one end of the car and a horizontal grab iron 7a secured to one end of a side sill 7 above the step 9, the hand operated brake actuating mechanism with which the cars 55 are provided being located on the end sill 8 adja-

cent the step 9 in such position that a trainman standing on the step 9 may actuate the brake actuating mechanism with his right hand.

In accordance with the preferred illustrated embodiment of my invention involving a grab- 5 iron mounted on the car and movable into and out of operative position as hereinafter stated, I provide the grab iron in the form of a round bar 10 provided with a head 11 at its upper end and with pins 12 and 13 extending crosswise through 10 the bar and projecting therebeyond at opposite sides thereof as shown.

The bar 10 is vertically slidable and revoluble in guide means on the car shown as comprising an upper bracket 14 and a lower bracket 15 pro- 15 vided with vertically aligned round openings there- through and secured to the deck and one of the side sills 7, respectively.

The lower bracket 15 is provided in its upper side with diametrically-opposed upwardly-opening notches 16 and contains lateral diametrically opposed recesses 17 which open vertically there- 20 through and into the opening through the bracket and occupied by the bar 10, the recesses 17 being shown as disposed at 90° angles to the notches 16. 25

On the underside of the bracket 15 are diamet- 20 rically opposed double face cams 18 disposed at 90° to the recesses 17.

The bar 10 extends slidably and rotatably 30 through the vertical openings in the brackets 14 and 15 and in the lowered position of the bar, as shown by the dotted lines in Fig. 3, in which its upper end extends below the top surface of the deck 6, it rests at its head 11 on the bracket 14, this position representing the one occupied 35 by the bar during loading or unloading of the car.

To position the bar 10 to extend above the deck 6 to the desired position for functioning as a grab-iron, the operator grasping the bar at 40 the pin-portion 13, pushes upwardly on the bar, the projecting ends of the pin 12 in striking the cams 18 and riding upwardly along their inclined surfaces causing the bar 10 to rotate into a position in which these projecting pin ends 45 become vertically aligned with the recesses 17, whereupon the operator continues upward thrust on the bar moving it to a position in which the ends of the pin 12 extend above the upper surface of the bracket 15. Upon then rotating the 50 bar to register the ends of the pin 12 with the notches 16 and allowing the bar to lower the pin ends enter the notches 16 and seat therein as shown in Fig. 1 in which position of the bar it is admirably disposed to serve as a grab iron 55

either as an aid to the trainman in mounting the flat car or in the operating with his one hand the hand operated brake actuating mechanism while holding on with the other hand.

5 To lower the bar from operative position to the lower, dotted, position shown in Fig. 3 to remove obstruction thereby to the loading or unloading of the car, the operator lifts the bar 10 to remove the pin 12 from the notches 16 and 10 rotates the bar to aline the pin with the recesses 17 whereupon he permits the bar to descend to the lower position.

While I have illustrated and described a particular construction embodying my invention, I 15 do not wish to be understood as intending to limit it thereto as the same may be variously modified and altered without departing from the spirit of my invention.

What I claim as new, and desire to secure by 20 Letters Patent, is:

1. In a flat car, the combination with its deck and step, of guide means comprising a member located adjacent said step and having an upwardly extending opening, and a grab iron slideable up and down in the opening in said member into and out of a position in which it projects above said deck into operative position and 25 rotatable in said member, and means for releasably holding said grab iron in raised position comprising a projection on said grab iron and an upwardly opening notch in said member adapted to receive said projection in the raised position of said grab iron, said member containing a lateral recess communicating with said opening and disposed in a different position an-

5 gularly about the axis of said member than said notch and through which recess said projection is adapted to pass when in registration therewith, the underside of said member having a cam engageable by said projection for automatically rotating said grab iron, in the raising of the latter, toward a position in which said projection registers with said recess.

2. In a flat car, the combination with its deck and step, of guide means comprising a member located adjacent said step and having an upwardly extending opening, and a grab iron slideable up and down in the opening in said member into and out of a position in which it projects above said deck into operative position and 10 rotatable in said member, and means for releasably holding said grab iron in raised position comprising diametrically disposed projections on said grab iron and upwardly opening diametrically opposed notches in said member adapted 15 to receive said projections in the raised position of said grab iron, said member containing diametrically opposed lateral recesses communicating with said opening and disposed in different positions angularly about the axis of said member than said notches and through which recesses said projections are adapted to be passed when in registration therewith, the underside of said member having diametrically opposed cams thereon engageable by said projections for automatically rotating said grab iron, 20 in the raising of the latter, toward a position in which said projections register with said recesses.

AUGUSTUS F. KLASING. 35
